CLAIM

I claim the ornamental design for a cell phone carrier, as shown and described.

DESCRIPTION

FIG. 1 is a front and left side perspective view of the cell phone carrier according to the present design;

FIG. 2 is a front view of the cell phone carrier;

FIG. 3 is a side view of the cell phone carrier;

FIG. 4 is a front and right side perspective view of the cell phone carrier;

FIG. 5 is a rear view of a cell phone carrier;

FIG. 6 is a top view of the cell phone carrier; and,

FIG. 7 is a bottom view of the cell phone carrier.

The broken line showing of environment in the drawing figures is for illustrative purposes only and forms no part of the claimed design.
